(57) **CLAIM**

The ornamental design for a convection steamer, as shown and described.

DESCRIPTION

FIG. 1 is a front view of a convection steamer showing my design;

FIG. 2 is a rear view of the convection steamer of FIG. 1; FIG. 3 is a top view of the convection steamer of FIG. 1; FIG. 4 is a bottom view of the convection steamer of FIG. 1; and,

FIG. 5 is a side view of the convection steamer of FIG. 1. The portion of the Figures shown in broken lines is for illustrative purposes only and forms no part of the claimed design.

1 Claim, 3 Drawing Sheets

FIG. 1
